UNITED STATES PATENT OFFICE.

GEORGE L. WAITT, OF BUFFALO, NEW YORK.

CHAPLET FOR MOLDING.

Application filed April 4, 1925. Serial No. 20,727.

The present invention is an improved chaplet for use in molding to prevent displacement of the core in molds or molding flasks.

5 The object of the invention is the production of a more durable chaplet using less metal in its construction while at the same time giving more support and strength thereto, due to its particular construction, 10 as a consequence rendering the chaplet more compact, more evenly balanced, and utilizing all material of the blank from which it is made.

Broadly, the invention resides in a chaplet 15 of maximum compression strength for the amount of metal used in its construction. The struts are obtained by cutting the blanks one from the center, and the other from the outer edge of the blank which carries 20 a suitable extension for this purpose. The struts are bent to extend at right angles and, because of the manner in which they are obtained, are of a width or length to support a maximum surface of the top and 25 bottom plates. The free ends of the struts may be bent at any desired angle to give added strength and rigidity thereto, the opening formed by bending the strut obtained from the center of the blank enabling 30 the metal to flow therethrough without obstruction.

The invention further resides in the sundry details of construction, combination and arrangement of parts shown and described, 35 and pointed out in the appended claims.

In this specification and the annexed drawings, the invention is disclosed in the form in which it is considered to be the best, but the invention is not limited to such form 40 because it is capable of being embodied in other forms; and it is to be understood that in and by the claims following the description herein it is intended to cover the invention in whatever form it may embody 45 within the scope thereof.

In the drawings which show the preferred embodiment of the invention as at present devised:—

Figure 1 is a plan view of a blank from 50 which the chaplet is made, its flexibility being indicated in dotted lines.

Fig. 2 is a front elevation of the chaplet constructed from the blank shown in Fig. 1.

Fig. 3 is a horizontal sectional view taken 55 substantially on lines 3—3 of Fig. 2.

Fig. 4 is a plan view of a blank for a slightly modified form of chaplet.

Fig. 5 is a front elevation of the chaplet constructed from the blank shown in Fig. 4.

Fig. 6 is a horizontal sectional view taken 60 substantially on line 6—6 of Fig. 5.

Fig. 7 is a plan view of a blank similar to that shown in Fig. 1, but produces a chaplet which is a multiple of that shown in Fig. 2.

Fig. 8 is a side elevation of a completed 65 chaplet made in the form shown in Fig. 7, its flexibility being indicated in dotted lines.

Fig. 9 is a cross-section of the chaplet shown in Fig. 8, taken substantially on lines 70 9—9 of Fig. 8.

Fig. 10 is a horizontal sectional view taken substantially on lines 10—10 of Fig. 8.

Referring particularly to the drawings, in which like characters denote similar and like parts referred to in the specification, 75 and referring particularly to Fig. 1, 1 indicates an elongated blank of desirable width and length to provide the chaplet shown in Fig. 2, which is substantially square. The blank has formed thereon a lateral extension α at a medial portion of one edge, as shown. The blank 1 may be stamped from a strip of sheet stock and during the operation may be cut to produce the various slits or cuts for forming wing flanges or struts 2. 85

The blank is cut transversely along the medial portion thereof to provide parallel slits $a—b$ and $c—d$, the slits $a—c$ and $b—d$ being spaced and in alignment. The slits $c—d$ extend across the greater portion of 90 the width of the blank between its side edges and are connected at their ends nearest the extension α , by a slit or cut i . The end or marginal portions 3 and 4 of the blank are folded toward each other on the dotted 95 lines j , which are coincident with said parallel cuts and thus provide the top and bottom plates, respectively, of the chaplets, as clearly seen in Figs. 2 and 3. The parts 5 lying between the parallel cuts above described form connecting uprights, integral with one edge of the top and bottom plates 3 and 4. From the drawings it will be observed that the extension α forms part of 100 one strut, while the other strut is obtained entirely from the center of the blank, the struts 2 being integral with one edge of each upright 5, and each adjacent strut being connected to the corresponding edge of 105 the adjacent uprights.

110

This manner of cutting the blanks produces chaplets having their supporting elements distributed to support the top and bottom plates at points most needed and 5 produces wider struts which will extend a greater distance between the plates 3 and 4, whereby greater compression strength is obtained in a more compact form. The struts 2 are bent on the dotted lines *k* at right 10 angles to the uprights 5, and lie between the top and bottom plates. It will be clear that the present invention provides the struts 2 of a width which will extend across the top and bottom plates for a distance at least 15 one-half the width of said plates, for the purpose of giving to the outer free edges of the plates 3 and 4 the requisite support needed, while having definite uprights 5 at the back of the chaplet connecting the top 20 and bottom. The outer or free ends of the struts 2 are bent on a line *l* at an angle (which may be any desired angle) to the body of the struts to provide additional supports 7 between the top and bottom plates 25 3 and 4. Any suitable portion of the chaplet may be perforated to allow metal to flow therethrough.

Manifestly, by virtue of this construction, a chaplet of any desired length can be 30 made from a single strip of material with substantially no loss of material and with its supports equally distributed to give the greatest possible strength to the top and bottom plate; and when required, the construction may be in multiple, as shown in 35 Figs. 7 to 10, without destroying the equal balance or distributed support of the chaplets.

The form of chaplet shown in Figs. 7 to 40 10 may be constructed from a wider blank 6, as shown in Fig. 7, which is the same as the blank in Fig. 1 except for having an additional duplicate section. This duplication may be extended in any multiple for certain work where long chaplets are desired. The like and corresponding parts of the 45 blank and chaplets shown in Figs. 7 to 10 bear the same reference characters as in the preceding figures, except being raised by the exponent prime.

As indicated in Figs. 2 and 8, the chaplet is capable of being flexed to meet the desired requirements, due to the equal distribution of the supporting members 2 and 5.

55 In Fig. 4 another form of blank is shown, from which the chaplet shown in Figs. 5 and 6 is formed. The blank 8 is cut or otherwise formed to produce at its end side the outwardly projecting portions 9, which are 60 located at a medial point of said side edges and ultimately form the wing flanges which lie between the top and bottom plates 10 and 11. The width of the portions or flanges 9 is such as is desired for the size 65 of chaplet being made, and the blank is

cut inwardly on the line *m*, *n*, *o* and *p*, from said end edges and on opposite sides of the wings 9, as clearly shown in Fig. 4. The portions 10 and 11, which form the top and bottom plates, are bent towards each other 70 and on lines coincident with the cut *m* and *o*, and *n* and *p*, to right angular position with respect to the center portion 12, which forms a relatively wide upright; but, in order to permit a free flow of the molten 75 metal about the chaplet, this upright 12 may be perforated. The wing flanges 9 are bent on lines *q* and *r* to lie at right angles between the top and bottom plates 10 and 11, and extend transversely across the latter for 80 a distance at least, but preferably greater, than one-half the width of said plates. The outer or free ends of the wing flanges 9 are bent on lines *s* and *t*, respectively, to extend at any desired angle to the body of said 85 flanges 9, for the purpose of giving additional support to the plates 10 and 11, in the direction of their length, as shown in Figs. 5 and 6.

From the foregoing it will be observed 90 that chaplets of greater durability and strength are provided, using a minimum of stock and being compact in construction and well balanced.

Having thus described the invention what 95 I claim as new and upon which it is desired to secure Letters Patent, is:

1. A chaplet comprising top and bottom plates, uprights spaced from each other and connecting said plates at one edge of the 100 plates and struts on the corresponding edges of said uprights, there being only one strut on each upright, said struts extending at substantially right angles with respect to the upright and lying between said plates. 105

2. A chaplet formed from a blank of material comprising a top and bottom plate and plurality of uprights equally spaced from each other and connecting said top and bottom plates at one edge of the said plates, 110 struts on corresponding edges of said uprights, the portions of said blank between said uprights forming a single strut between the adjacent uprights, said uprights being connected respectively with one strut only, 115 said struts extending at right angles with respect to the uprights substantially across and between said plates.

3. A chaplet comprising top and bottom plates, uprights spaced from each other and connecting said plates at one edge of the 120 plates and struts on corresponding edges of said uprights, there being only one strut on each upright, said struts extending at substantially right angles with respect to the 125 upright and lying between said plates, the free end portion of said flanges extending at an angle to the body of the struts.

4. A chaplet formed from an elongated blank of sheet material, the medial portion 130

of a longitudinal edge of the blank having a lateral extension thereon, the end portions of the blank being extended to superposed position to form top and bottom plates, the center of the medial portion being cut to form a strut extended between said plates and providing uprights at two corner portions of the plates, said strut being integral with one of said uprights and said extension being extended between said plates to form another strut integral with the other of said uprights.

In testimony whereof I have hereunto set my hand.

GEORGE L. WAITT.
